PAIR OF SPECTACLES FOR EYE MAKEUP

Charles Baratelli, Reading, Pa., assignor to Gladys W. Holloway, Los Angeles, Calif.

Filed Aug. 21, 1961, Ser. No. 66,442

Term of patent 3½ years

(Cl. D57—1)

FIG 1

FIG 5

FIG. 1 is a front perspective view of a pair of spectacles for eye make-up, showing my new design;

FIG. 2 is a top plan view thereof;

FIG. 3 is a side elevational view thereof;

FIG. 4 is a front elevational view thereof; and

FIG. 5 is a rear elevational view thereof.

I claim:

The ornamental design for a pair of spectacles for eye make-up, as shown.
